UNITED STATES PATENT OFFICE.

JOHN J. DALY, OF NEW BRUNSWICK, NEW JERSEY, ASSIGNOR TO THE BANKER MANUFACTURING COMPANY, OF NEW BRUNSWICK, NEW JERSEY, A CORPORATION OF NEW JERSEY.

DOOR-CHECK.

1,131,122.

Specification of Letters Patent.

Patented Mar. 9, 1915.

Application filed December 30, 1914. Serial No. 879,628.

To all whom it may concern:

Be it known that I, JOHN J. DALY, a citizen of the United States of America, and a resident of New Brunswick, in the county of Middlesex and State of New Jersey, have invented certain new and useful Improvements in Door-Checks, of which the following is a specification.

This invention relates particularly to door-checks of the pneumatic type in which one part, usually the door, carries a cylinder and piston the movement of which is fluid checked, and the other part, usually the door-jamb, carries an anchorage for a flexible connection with the piston.

The check is applicable especially to screen-doors, and other doors of light construction in which the hinge-line is not at too great a distance back of the face of the door to which the check is attached.

The object of the invention is to provide a form of door-check which may be readily fitted to doors of different thicknesses, in which the springs for effecting the closure of the door are combined, in which they are protected from injury, and in which the piston is protected from oblique strain.

In the accompanying sheet of drawings which forms a part of this application, Figure 1 is a plan of a door just about to close carrying a door-check embodying my invention, the cylinder being in section, and Fig. 2 is a plan with the door in full open position and the door-check being in section.

The door-check comprises a cylinder 1 with a head 2 carrying an outlet 3 from the cylinder which is adjustable by a screw 4. The head is hinged to a plate 5 which is attached to the face of the door opposite from the hinge line 6 of the door. A piston travels in the cylinder and consists of a metal head 7 and a washer 8 screwed to the head and clamping between them a leather cup-packing 9. Both the head and the washer fit the cylinder closely and are spaced apart so as to hold the piston in alinement in the cylinder. Holes 10 through the washer admit air under the flange of the packing. A piston-rod 11 is connected with the piston-head through a ball joint 12 and therefore

does not serve to hold the piston in alinement, a function which it cannot perform since it is not always guided at the mouth of the cylinder and is liable to be thrown out of alinement when the piston is near the bottom of the cylinder with the door closing and its momentum putting all the parts under compression. In Fig. 1, the piston-rod is shown out of the center line of the cylinder because it is under compression and it is not guided by the mouth of the cylinder. When the door has fully closed and the air pressure is fully discharged, the spring will put the piston-rod under tension and draw it into the center line of the cylinder. A spring 13 forces the piston toward the bottom of the cylinder, and, except when the checking action is taking place, puts the connecting parts under tension. A plate 14 is attached to the door-jamb and has pivoted thereto an arm 15 which is drawn into an erect position by a spring 16. The end of the piston-rod and the end of the arm are connected by an extensible link consisting of an outer sleeve 17 and an inner sleeve 18 telescoping together and protecting a tension spring 19 which draws the ends together.

The effectiveness of the springs in closing the door is increased by holding the line of links as far as possible from the hinge-line. On the other hand, by permitting the line of links to closely approach the hinge-line, the door can be allowed to be swung open against the wall as shown in Fig. 2 without undue length of cylinder and other parts. The spring attached to the arm which projects from the door-jamb throws the arm outward as soon as the door commences to close and thereby affords sufficient leverage for the other springs to draw the door shut.

What I claim as new, and desire to secure by Letters Patent of the United States, is—

1. In a door-check, a cylinder adapted to be connected to a door, a piston fitting therein, a piston-rod, a plate adapted to be secured to the door-jamb, an arm pivoted to the plate, a spring for drawing the arm into an erect position, and an extensible link

connecting the end of the arm and the end of the piston-rod, substantially as described.

2. In a door-check, a cylinder adapted to be connected to a door, a piston fitting there-in, a piston-rod, a plate adapted to be secured to the door-jamb, an arm pivoted to the plate, a spring for drawing the arm into an erect position, and a link consisting of spring-controlled telescoping parts connect-

ing the end of the arm and the end of the 10 piston-rod, substantially as described.

Signed at New Brunswick, N. J., this 29th day of December, 1914.

JOHN J. DALY.
